[57] ABSTRACT

A device for stacking bags at the outlet of a bag-forming machine, comprising a conveying belt, control means imparting an intermittent movement thereto, a stop extending cross-wise to the belt movement direction and control means for imparting an alternating motion thereto to release a bag stack for conveying by said belt, and means bearing on said bag stack during forming thereof with a contacting part moving together with said bag stack.

1
STACKING DEVICE

This invention has for object a device to be arranged at the outlet of a machine, particularly a machine for shaping plastic bags, said device being so designed as to allow on the one hand the formation of a bag stack and on the other hand the removal of the formed bag stack, said device comprising an endless conveying belt on which the bags are stacked, control means to impart to said belt an intermittent movement through either a bag-counting apparatus or an apparatus measuring the bag stack height, a stop extending cross-wise to the belt movement direction and against which the bag stack is formed, and control means synchronized with the belt control means for imparting to the stop an alternating motion so as to release the formed bag stack and allow the removal thereof by said belt.

Devices of this kind presently known have the drawback that when the bag stacks are released by the movable stop and taken along by the endless belt, said bag stacks spread on said belt under the combined action of inertia and of the lack of adhesion of the material used. It is thus necessary for the person who checks the bag stacks at the outlet from the device, to reform said stacks before packaging same. If such a stack-reforming job may be considered as possible at the outlet from low-output bag-forming machines, it is not the case with high-output machines where it is necessary to have two operators to release in due time the bags from the device and to reform the bag stacks.

The invention has for object to obviate said drawback and to provide a stacking device which allows whatever be the production rate of the bag-forming machine, to retain the bags perfectly arrayed in stacks down to the outlet of said device where said stacks may be released manually by a single operator or taken over mechanically to be conveyed to some other place.

For this purpose according to the invention, said device comprises means so arranged as to bear on the upper side of the bag stack by the moment where said stack is formed, control means being provided to impart to said means an alternating motion to move same towards and away from said upper side, said bearing means being so arranged that the part thereof engaging the bag stack upper side moves with the same linear speed as the endless belt and along the same direction as said belt.

In a further embodiment of the invention, second control means are provided to positively drive the bearing means with the same linear speed as the endless belt and along the same direction as said belt.

In an advantageous embodiment, the control means for the stop and the control means for moving said bearing means towards or away from the bag upper side are synchronized and comprise a single driving member, said control means being so arranged that the bearing means bear on the bag stack upper side by the moment where the stop retaining said stack has been completely separated from the endless belt and has released the bag stack.

In a particularly advantageous embodiment of the invention, the endless belt control means and the bearing means second control means comprise a single driving member for driving the belt and said means along the same direction and with the same linear speed.

Other details and features of the invention will stand out from the description given below by way of non

limitative example and with reference to the accompanying drawings, in which:

FIG. 1 is an elevation view with parts broken away of the device according to the invention.

5 FIG. 2 is a diagrammatic plan view of the device shown in FIG. 1.

FIG. 3 is an elevation view with parts broken away of another embodiment of the device shown in FIG. 1.

10 In the various figures, the same reference numerals pertain to similar elements.

The device according to the invention and shown in FIGS. 1 and 2 is to be arranged at the outlet of a machine for forming plastic bags (not shown) so as to allow the formation of a bag stack and the removal of

15 the formed bag stack. The device comprises an endless belt on which the bags are stacked, an adjustable-position stop 2 against which the bags come to stop by the stacking thereof as well as a fixed stop 3, the spacing between both said stops being set according to the

20 bag dimensions in such a way that said spacing be substantially equal to that bag dimension in parallel relationship with the lengthwise axis of belt 1. The movements of belt 1 are intermittent and they are controlled in a way known per se, from a motor with reduction gearing 4 and through a bag-counting apparatus (not shown), said apparatus also acting on the control means for the stop 2 which are so synchronized with the control means for belt 1 as to impart thereto an alternating motion to cause the stop 2 to move away from

25 the belt to leave a passage between said stop and belt 1 so as to allow the removal of a formed bag stack, and to return afterwards to its position against said belt, the belt movement only occurring when the stop 2 has completely released the passage for the bag stack. The device control means are so arranged as to act upon the bag-forming machine control means to stop said machine when the belt is driven. However with low production rate machines, it is possible to perform the

30 stacking device cycle during the formation of a bag. In such a case, the machine does not have to be stopped during the movement operations for the already formed bag stack. To prevent spreading of the bag stack on belt 1 as said belt starts to move, the device

35 comprises means 5 arranged to bear on the stack upper side when said stack is formed and before belt 1 starts to move, control means 6 being provided to impart an alternating motion to said bearing means so as to bring them towards and away from the bag stack, said bags

40 being so arranged that the area thereof engaging the upper side of the stack of bags 7 (shown in dotted lines in FIG. 1) moves with the same linear speed as the belt 1 and along the same direction as said belt. The means 5 advantageously comprise a cylinder 8 in parallel relationship with the belt 1 and with the axis thereof at

45 right angle to the movement direction of said belt, said cylinder 8 being mounted on a shaft 9 in such a way that said cylinder rotates freely on said shaft. The control means 10 for imparting to the stop 2 said alternating motion and the control means 6 for the alternating

50 motion of cylinder 8 comprise for bringing same away from and nearer to the belt 1, in opposite directions, in such a way that said cylinder bears on the stack when the stop 2 has released a passage thereon, a single driving member 12. The stop 2 is arranged on two uprights

55 13 and 13' while the cylinder is arranged on two uprights 14, 14', said uprights 13, 13', 14, 14' being in parallel relationship and so guided as to be simulta-

60 neously moved in opposite directions by the member 12.

65 The cylinder 8 is arranged on two uprights 14, 14', said uprights 13, 13', 14, 14' being in parallel relationship and so guided as to be simulta-

neously movable by pairs (13, 13') and (14, 14') along the lengthwise axis thereof which lies substantially at right angle to that plane going through side 15 of belt 1, each one of said uprights being provided with a rack 16, the racks 16 of the upright pairs (13, 14) and (13', 14') facing one another and a pinion 17 meshing with both racks 16 of each one of said last upright pairs located on either side of belt 1 so as to move simultaneously the uprights of each pair (13, 14) and (13', 14') along opposite directions, both pinions 17 being made fast to a single shaft 18 which is rotated by means of a rack 19, which meshes with a gear wheel 20 integral with shafts 18, said driving member 12 being advantageously operated by a jack 21 which bears on the piston rod thereof, the rack 19. Each pair of said uprights (13, 14) (13', 14') is arranged on a frame 22 which is so movable as to adjust the position of stop 2 according to the bag dimensions, said frames 22 being joined together so as to move simultaneously and in parallel relationship with the movement direction of belt 1 under the action of pinions 23 driven by a hand-wheel 24 and which mesh with two racks 25 which are attached to the device frame 24. Cylinder 8 might under the action of the bag stack on which it bears, be rotated by friction about the axis thereof with the same linear speed as the belt 1 and thus retain the bag stack perfectly formed and this due to said stack being clamped between the cylinder 8 and belt 1. In the embodiment of the device shown in the drawings, cylinder 8 is so arranged as to be positively driven from the power cylinder 27 and by motor 4 and chain 28, with the same linear speed and along the same direction as belt 1. Said positive driving of cylinder 8 is performed by means of two belts 29 arranged on either side of endless belt 1 in parallel relationship therewith, cooperating with cylinder 27 and so arranged as to have the portions 30 thereof extending on the path of cylinder 8 when said cylinder moves to bear on the bag stack, said cylinder 8 thus being driven by friction by the belts as soon as endless belt 1 moves to discharge a bag stack. Return pulleys 31 are provided for the belts 29 on the frames 22, said belts being provided as well as endless belt 1, with a spring tensioning device (not shown). The control means for jack 21 attached to one frame 22, and the control means for motor 4 are so arranged that said motor is energized to drive belt 1, belts 29 and cylinder 8 when said jack has brought said cylinder in engagement with the bag stack and belts 29 and when stop 2 has released belt 1. The stacking device further comprises advantageously a blowing ramp 32 which is arranged in parallel relationship and cross-wise to the belt 1 between the outlet of the bag-forming machine and stop 2, said ramp supplied with low-pressure air being so directed as to rapidly bring the bags down on belt 1 or on the bag stack being formed and thus to prevent with a high production rate of the machine, the bags floating and colliding with the following bags before laying said bags down on the stack.

The device according to the invention and shown in FIG. 3 is so designed as to allow the formation of a bag stack and the stocking on endless belt 1, of a determined number of formed stacks. To retain said formed bag stacks perfectly arrayed by the intermittent movements of belt 1, auxiliary cylinders 8' are associated to cylinder 8, the total number of cylinders being equal to the number less one of bag stacks to be stocked on belt 1 so as to release that bag stack farthest away from cylin-

der 8 and to cooperate with each formed stack in the same way as the cylinder 8 acting upon the newly-formed stack, said cylinders 8 and 8' being parallel, lying at the same level and being regularly spaced from one another in such a way that each one of said cylinders might bear on the upper side of the corresponding stack of bags 7 substantially in the same location on said side, means 33 and 34 being provided to operate the cylinders 8' in such a way that the movements thereof be identical and simultaneous with the movements of cylinder 8. To allow adjusting the position of cylinders 8' according to the bag dimensions, each cylinder 8' is mounted on two parallel uprights 13, 13' similar to those uprights which support cylinder 8, said uprights 13, 13' for each cylinder 8' being arranged on a movable frame 35 which is controlled so as to move in parallel relationship with the lengthwise axis of belt 1, by a pinion 36 which is controlled by a hand wheel 37 and which meshes with the rack 25 attached to the device frame 26. Said means 33 are provided to rotate about the shaft 9' thereof the cylinders 8' with the same speed as cylinder 8 and said means 33 comprise on the one hand a belt 38 cooperating with each one of cylinders 8 and 8' and driven by cylinder 8 and on the other hand, a resilient member 39 insuring tensioning of said belt 38 whatever be the spacing between cylinders 8 and 8'. Means 34 are provided to control the upwards and downwards movement of cylinders 8' from gear wheel 20 which controls cylinder 8 and said means comprise on the one hand a chain 40 cooperating with each one of pinions 41 provided for driving at the same speed, those uprights 13, 13' which support cylinders 8' and on the other hand, a resilient member 42 insuring tensioning of chain 40 whatever be the spacing between cylinders 8 and 8'.

It must be understood that the invention is in no way limited to the above embodiments and that many changes may be brought therein without departing from the scope of the invention as defined by the appended claims.

I claim:

1. A device to be arranged at the outlet of a bag-shaping machine for allowing the formation of a bag stack and the removal of the formed bag stack, said device comprising and endless conveying belt on which the bags are stacked, belt control means to impart to said belt an intermittent movement through, a bag stack measuring device, a stop extending cross-wise to the belt movement direction and against which the bag stack is formed, and stop control means synchronized with the belt control means for imparting to the stop an alternating motion so as to release the formed bag stack and allow the removal thereof by said belt, bearing means so arranged as to bear on the upper side of the bag stack when said stack is formed, and when said stop control means releases the formed bag stack, bearing control means being provided to impart to said bearing means an alternating motion to move same towards and away from said upper side, said bearing means being so arranged that the part thereof engaging the bag stack upper side moves with the same linear speed as the endless belt and along the same direction as said belt to prevent spreading of the bag stack on said belt.
2. Device as claimed in claim 1, in which second control means are provided to positively drive the bearing means with the same linear speed as the endless belt and along the same direction as said belt.

3. Device as claimed in claim 2, in which the endless belt control means and the bearing means second control means comprise a single driving member for driving the belt and said bearing means in the same direction and with the same linear speed.

4. Device as claimed in claim 2, in which said bearing means comprise at least one cylinder in parallel relationship with the belt and with the axis thereof at right angle to the endless belt moving direction, said cylinder being so mounted on a shaft as to rotate freely about the axis thereof.

5. Device as claimed in claim 4, in which said cylinder is arranged on two parallel uprights, guides being provided to allow said uprights to move simultaneously under the action of said bearing control means, along the lengthwise axis thereof which is substantially at right angle to that plane going through that endless belt side on which the bags are stacked.

6. Device as claimed in claim 1, which comprises a blowing ramp arranged in parallel relationship and cross-wise to the endless conveying belt between the bag-forming machine outlet and said stop, said ramp being so directed as to bring the bags down on the conveying belt and on a bag stack being formed.

7. Device as claimed in claim 1, in which a fixed stop is provided in parallel relationship with the movable stop, between said movable stop and the bag-forming machine outlet, the spacing between both said stops corresponding substantially to the dimension of one bag in parallel relationship with the endless conveying belt lengthwise axis.

8. A device to be arranged at the outlet of a bag-shaping machine for allowing the formation of a bag stack and the removal of the formed bag stack, said device comprising: an endless conveying belt on which the bags are stacked; belt control means to impart to said belt an intermittent movement through; a bag stack measuring device a stop extending cross-wise to the belt movement direction and against which the bag stack is formed; stop control means synchronized with the belt control means for imparting to the stop an alternating motion so as to release the formed bag stack and allow the removal thereof by said belt; bearing means so arranged as to bear on the upper side of the bag stack when said stack is formed and when said stop control means releases the formed bag stack; bearing control means provided to impart to said bearing means an alternating motion to move same towards and away from said upper side, said bearing means being so arranged that the part thereof engaging the bag stack upper side moves with the same linear speed as the endless belt and along the same direction as said belt to prevent spreading of the bag stack on said belt, said stop control means and said bearing control means being synchronized and comprising a single driving member and being so arranged that the bearing means bear on the bag stack upper side when the stop retaining the stack has been completely separated from the endless belt and has released the bag stack.

9. A device to be arranged at the outlet of a bag-shaping machine for allowing the formation of a bag stack and the removal of the formed bag stack, said device comprising: an endless conveying belt on which the bags are stacked, said belt being looped over a driven cylinder; belt control means to impart to said belt an intermittent movement through a bag stack measuring device; a stop extending cross-wise to the

belt movement direction and against which the bag stack is formed; stop control means synchronized with the belt control means for imparting to the stop an alternating motion so as to release the formed bag stack and allow the removal thereof by said belt; bearing means including a freely rotating cylinder disposed parallel to and transverse to said belt and arranged to bear on the upper side of the bag stack when said stack is formed and when said stop control means releases the formed bag stack; bearing control means being provided to impart to said bearing means an alternating motion to move same towards and away from said upper side; second control means to positively drive the bearing means so that the freely rotating cylinder engaging the bag stack upper side moves with the same linear speed as the endless conveying belt and in the same direction as said belt to prevent spreading of the bag stack on said belt, endless conveying said second control means comprising at least one belt in parallel relationship with the said endless conveying belt and driven by said driven cylinder, said one belt being so arranged as to have a portion thereof extending in the path of the freely rotating cylinder when the latter moves to bear on the bag stack, said freely rotating cylinder being driven by friction by said one belt when said endless conveying belt is operated to move the formed bag stack.

10. A device to be arranged at the outlet of a bag-shaping machine for allowing the formation of a bag stack and the removal of the formed bag stack, said device comprising: an endless conveying belt on which the bags are stacked; belt control means to impart to said belt an intermittent movement through a bag stack measuring device; a stop supported by two parallel first uprights and extending cross-wise to the belt movement direction and against which the bag stack is formed; guides for guiding the uprights for movement along paths coinciding with their axes; a facing rack carried by each of said guides; stop control means synchronized with the belt control means for imparting to the stop an alternating motion so as to release the formed bag stack and allow the removal thereof by said belt; bearing means including two parallel second uprights supporting a freely rotating cylinder which is disposed parallel to and transverse to said belt and arranged to bear on the upper side of the bag stack when said stack is formed and when said stop control means releases the formed bag stack, said bearing means further including guides for guiding the uprights to move along paths coinciding with their axes; a facing rack carried by each of said last-named guides; pinion means associated with all said facing racks for moving said first and second uprights in opposite directions; stop control means being provided to impart to said bearing means an alternating motion to move same towards and away from said upper side; second control means to positively move the bearing means so that the freely rotatable cylinder engaging the bag stack upper side moves with the same linear speed as the endless conveying belt and in the same direction as said belt to prevent spreading of the bag stack on said belt.

11. A device as claimed in claim 10, in which each said upright pairs is arranged on a frame which is movable so as to allow adjusting the stop position according to the bag size, said frames being joined together so as to move simultaneously in parallel relationship with the endless belt movement direction under the action of at

least one pinion meshing with a rack attached to the device frame.

12. A device to be arranged at the outlet of a bag shaping machine for allowing the formation of a bag stack and the removal of the formed bag stack, said device comprising: an endless conveying belt on which the bags are stacked, control means to impart to said belt an intermittent movement through a bag stack measuring device; a stop extending cross-wise to the belt movement direction and against which the bag stack is formed; stop control means synchronized with the belt control means for imparting to the stop an alternating motion so as to release the formed bag stack and allow the removal thereof by said belt; bearing means including a freely rotating cylinder disposed parallel to and transverse to said belt and arranged to bear on the upper side of the bag stack when said stack is formed, when said stop control means releases the formed bag stacks; bearing control means being provided to impart to said bearing means an alternating motion to move same towards and away from said upper side; second control means to positively drive the bearing means so that the freely rotating cylinder engaging the bag stack upper side moves with the same linear speed as the endless conveying belt and in the same direction as said endless conveying belt to prevent spreading of the bag stack on said belt; and auxiliary cylinders associated with said freely rotating cylinder, the total number of cylinders being equal to the number less one of the bag stacks to be stacked on said conveying belt, said cylinders being in parallel relationship, located at the same level and regularly spaced from one another in such a way that each cylinder may bear on the corresponding stack upper side substantially in the same location on said side; and means to operate the auxiliary cylinders in such a way that the movements thereof are identical and simultaneous with

the movements of the freely rotating cylinder.

13. A device as in claim 12, in which each one of the auxiliary cylinders associated with said freely-rotating cylinder is mounted on two parallel uprights similar to the uprights supporting said freely rotating cylinder, the uprights of each said auxiliary cylinders being arranged on a movable frame so as to allow adjusting the cylinder position according to the bag size, each frame being controlled for a movement in parallel relationship with the conveying belt movement, by a pinion meshing with a rack attached to the device frame.

14. A device to be arranged at the outlet of a bag shaping machine for allowing the formation of a bag stack and the removal of the formed bag stack, said device comprising a conveyor on which the bags are stacked, conveyor control means to impart to said conveyor an intermittent movement through a bag stack measuring device, a stop extending cross-wise to the conveyor movement direction and against which the bag stack is formed, and stop control means synchronized with the conveyor control means for imparting to the stop an alternating motion so as to release the formed bag stack and allow the removal thereof by said conveyor, bearing means so arranged as to bear on the upper side of the bag stack when said stack is formed and when said stop control means releases the formed bag stack, bearing control means being provided to impart to said bearing means an alternating motion to move said bearing means towards and away from said upper side of said bag stack, said bearing means being so arranged that the part thereof engaging the upper side of the bag stack moves with the same speed as the conveyor and along the same direction of movement as the conveyor to prevent spreading of the bag stack on the conveyor.
